Primary Examiner — Robert M Spear*Assistant Examiner* — Ryan Harvey(74) *Attorney, Agent, or Firm* — Blakely, Sokoloff, Taylor & Zafman LLP(57) **CLAIM**

The ornamental design for a wheeled torso exercise machine, as shown and described.

DESCRIPTION

FIG. 1 is a perspective view showing the new design for a wheeled torso exercise machine;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.
